K. YANO

GOLD DUST EXTRACTOR

Original Filed July 1, 1921

FIG. 1.

FIG. 2.

Inventor
Keizo Yano,

Attorney

UNITED STATES PATENT OFFICE.

KEIZO YANO, OF NISHIKU OSAKA, JAPAN.

GOLD-DUST EXTRACTOR.

Application filed July 1, 1921, Serial No. 481,893. Renewed February 28, 1925.

To all whom it may concern:

Be it known that I, KEIZO YANO, of No. 7 Sanchome Awaza-Kamidori, Nishiku Osaka, Japan, have invented certain new and useful Improvements in Gold-Dust Extractors, of which the following is a specification, reference being had therein to the accompanying drawing.

This invention consists in an improvement of a gold-dust extractor by amalgamation with a pipe to conduct gold-bearing mud-water, provided with inlets for mercury and outlet for amalgam. The special feature of this invention is that the parts of the water pipe where mercury is introduced are made to form vertical drums, with markedly larger section compared with the other parts, to diminish the velocity of water and to prevent floating motion of mercury particles. The drums are also provided with a vast number of small compartments to confine the amalgam formed, and a number of grid shelves, installed in the lower and upper parts of the same respectively. The outlet of the last drum ends in two small branch pipes whose exits are made to oppose each other, and retard water velocity to reduce loss of mercury to an extreme. It is the advantage of this invention that almost all of the defects experienced in other apparatuses of like nature known heretofore are got rid of by this invention nearly to perfection.

Figure 1 shows the side elevation, partly in section, of the general arrangement of this invention, while Figure 2 shows a side view of the manifest manner of pouring mercury, the same parts being denoted by the same symbol throughout all the drawings.

In this invention a stationary drum 3 is installed concentric around a revolving filter-drum 2, which latter contains a water-injection drum 1. At one end of 3 there are fitted two vertical pipes 4 and 4', with a centrifugal pump connected to the lower end of 4'. The pump 5 serves to give water a pressure head sufficiently large to aid the water head in the pipe 4 in forcing water and mercury layers to be mentioned hereafter upward in the drums.

The pipe 4 is extended further and bent over and over to form a series of vertical drums, only two of which are shown in the drawing by the symbols 9 and 10. The end of the last drum branches to two pipes 6

and 7, and the water from 6 is made to oppose that from 7. The lower end of 7 is extended downward to form a collector 8 for mercury and amalgam. 60

The section of the drums 9 and 10 is made considerably greater than the other parts to retard the velocity of water. As shown in the drawing, a nozzle-plate 11 is fitted at the lower end of each drum, with a nest of small nozzles 12. In the middle part of the drum, the shelves 13 and 13' are provided with numerous small compartments 14 and 14' to receive mercury. A number of grid shelves 15 provided with 70 many apertures 16 arranged in staggered relation are also installed in the upper part of 9 and 10. 65

Each drum has an inlet 17 for mercury and an outlet for amalgam 18 at the bottom 75 of the drum for tapping out the amalgam.

External to the drums, a working handle 19 is provided to work the nozzle-plate 11, giving the latter small displacement to ensure close mixing of mercury and gold-dust 80 by changing the direction of water jets.

The object of this invention is to separate and extract pure metal from metal-bearing gravel, for instance gold in alluvium, or the like, in a more efficient and economical way 85 than by other apparatus of like nature heretofore known, the working process being explained below.

The gold-bearing gravel is charged into the filter-drum 2 while mercury is supplied 90 to the drum 9 and 10 from the inlet 17 in a proper amount. The gravel set in rotation by the filter-drum 2 intermingles with water jets from the injection drum 1, and mud-water containing gold in more concentrated condition is led to flow down the water pipe 4, pebbles and coarse sand being rejected out from the filter. 95

A pressure head is given to the water coming down the pipe 4' by the pump 5, 100 and consequently the water delivered from the pump forces the mud-water from the pipe 4 to be injected upward through the nozzles 12 in the nozzle-plate 11. The energy given to the water jets is of such strength that the mercury introduced into the drum 9 is blown upward by the jets and confined into the compartments 14 and 14' on the shelves 13 and 13'. Moreover there is a sufficient energy left in the water to repeat similar action on the mercury in the succeeding drums 10 and so forth, after 110

passing through several layers of mercury and the apertures 16 in the grids 15 of the drum 9.

The water leaving the last drum is divided into two flows through the pipes 6 and 7, in opposite direction against each other, and the flow being retarded thus, the water finally makes exit from the overflow as shown by arrows in the drawing.

10 The mercury particles confined into the compartments 14 and 14' by the water pressure make close contact with particles of metallic gold in the mud-water, forming amalgam of the same. The comparatively slow velocity of flow due to enlarged area of the drum, the friction between the particles of mercury and the walls of 14 and 14' and the weight of mercury itself combine to prevent the tendency of mercury to flow outside the compartments, despite the said upward flow of water in the drum. Of a small percentage of the metal which reach the grids 15, greater portion is reflected downward by collision with the grids and confined again into the compartments 14 and 14'. Metallic particles escaping the drum 9 are similarly treated in the succeeding drums, resulting in a very high percentage of gold extraction.

30 Remnant gold and mercury which escape the extraction by the last drum are of very fine particles, and it will be very rarely the case. But they are also caught in the collectors 8 and recovered as deposits.

35 From the explanation given above, it will be obviously seen that this invention ensures the highest economy of mercury and an extremely high efficiency of gold extraction not attained by any other apparatus or processes for like purpose heretofore known.

40 What I claim is:

1. A gold-dust extractor comprising a charging drum for metal-bearing gravel, a revolving filter drum within the charging drum, a water injection drum within the filter drum, a series of amalgamation drums each provided with a plurality of nozzles, a shelf having compartments for amalgam, and shelves with apertures for flow of water within said amalgamation drums, all connected in series to form a continuous passage from the charging drum to and through the amalgamation drums, and pipes

connected with the last amalgamation drum, with their outlets directed to oppose each other, mercury being supplied into the amalgamation drums.

2. A gold-dust extractor as claimed in claim 1, having a pump, connected with the inlet end of the first amalgamation drum supplying pressure to pass the water-carrying liquid through mercury layers in the amalgamation drums.

3. A gold-dust extractor comprising a charging drum, a filter drum within the charging drum, a water injection drum within the charging drum delivering water to the filter, an amalgamation drum having an inlet and an outlet, a pipe connecting the charging drum and the inlet of the amalgamation drum, a plurality of nozzles adjacent the inlet of the amalgamation drum, a shelf having compartments for amalgam situated within the amalgamation drum beyond the nozzles and shelves with apertures for flow of water beyond said shelf.

4. A gold-dust extractor comprising a charging drum, a filter drum within the charging drum, a water injection drum within the charging drum delivering water to the filter, an amalgamation drum having an inlet and an outlet, a pipe connecting the charging drum and the inlet of the amalgamation drum, a plurality of nozzles adjacent the inlet of the amalgamation drum, a shelf having compartments for amalgam situated within the amalgamation drum beyond the nozzles and shelves with apertures for flow of water beyond said shelf, and outlets from said amalgamation drum, situated to oppose one another.

5. An amalgamator comprising an amalgamating drum containing mercury, means for forcing water through said drum under pressure, a water outlet, and means for diminishing the pressure of the water before it reaches such outlet, comprising passages through which the water flows in opposing directions.

In testimony whereof I have hereunto affixed my signature in the presence of two witnesses.

KEIZO YANO.
